DESIGN FOR A BOTTLE

Adele Simpson, New York, N. Y., assignor to Renoir Parfums, Ltd., New York, N. Y., a corporation of New York

Application January 17, 1947, Serial No. 136,211

Term of patent 14 years

(Cl. D58—9)

To all whom it may concern:

Be it known that I, Adele Simpson, a citizen of the United States, residing at New York city, in the county of New York and State of New York, have invented a new, original, and ornamental Design for a Bottle, of which the following is a specification, reference being had to the accompanying drawing, forming part thereof.

In the drawing:

Fig. 1 is a front elevational view of a bottle, showing my new design;

Fig. 2 is a side elevational view thereof; and

Fig. 3 is a top plan view.

I claim:

The ornamental design for a bottle, substantially as shown.

ADELE SIMPSON.
